DISTANCE FINDER

Filed Jan. 7, 1922

Patented Feb. 15, 1927.

1,617,612

UNITED STATES PATENT OFFICE.

JAMES MURRAY WASHBURN, OF CHICAGO, ILLINOIS.

DISTANCE FINDER.

Application filed January 7, 1922. Serial No. 527,556.

My present invention relates to improvements in distance finder of the type shown in my prior Patents 1,033,848, 1,033,849, and 1,033,850, dated July 30, 1912, the same being more especially designed for use in determining short distances for photographic purposes. However, this construction may be made in larger sizes and graduated to determine longer distances than those shown.

Among the objects of my invention are to improve upon the sighting mechanism of an instrument of the character described; to provide a more readily read, direct reading instrument; to provide a shade for the prism of the instrument so that glaring illumination cannot be reflected from the face of the prism toward the eye of the observer to interfere with observation and to prevent rays of light from other objects being reflected by the prism into an eye of the observer; to improve upon the mechanism by means of which the instrument is placed at a definite distance from the eye of the observer; to render the instrument more compact and capable of being carried in the user's pocket and such further objects, advantages and capabilities as will later more fully appear.

My invention further resides in the combination, construction and arrangement of parts illustrated in the accompanying drawing and, while I have shown therein a preferred embodiment, I desire the same to be understood as illustrative only and not as limiting my invention.

Referring more in detail to the drawing annexed hereto and forming a part hereof,

Fig. 1 is a diagram illustrating the use of my invention.

Fig. 2 is a perspective view of my improved form of instrument.

Fig. 3 is a similar view of the instrument in closed condition.

Fig. 4 is a longitudinal, horizontal section of the instrument opened up and showing the relationship of the parts within the instrument.

Fig. 5 is a longitudinal section substantially along the plane indicated by the line 5-5 Fig. 4.

Fig. 6 is a transverse section substantially along the plane indicated by the line 6-6 Fig. 4.

Referring more in detail to the annexed drawing, numeral 1 designates a casing and 2 a cover therefor, these two parts being

hinged at 3 and being provided with fastening means 4 to hold the instrument closed. The casing 1 comprises a pair of end members 5 and 6, which may either be castings as shown or be formed of properly folded sheet metal, or made in any other appropriate manner, and a pair of side members 7 and 8. These parts are suitably secured together by any appropriate means such as screws 9. This arrangement is such that the opposite edges of the casing 1 are left open, and within this casing is fixedly mounted a prism 10, suitably secured as by having its ends inset slightly into the end pieces 5 and 6. Pivoted at one end of one of the edge openings is a shield 11 having a top 12. The purpose of this shield is to prevent, so far as possible, the entrance of light into the casing to thereby reduce to a minimum the reflection of light to the observer's eye from the face of the prism toward him. When this shade or shield 12 is closed it may be opened by means of an indentation or small projection 13 opposite a notch 14 in the plate 8.

The end piece 5 is hollowed out as shown in Fig. 4 for the reception of a reel 15 within which is mounted a spring 16 to cause the reel to wind up a cord 17 by means of which, when the same is unwound, the instrument may be held at the proper predetermined position from the observer's eye. To assist in this operation, a tab 18 is secured adjacent the free end of the cord 17 and has an aperture 19 in one end thereof to permit the user to look therethrough when sighting upon an object. In order to facilitate getting this tab 18 close to the observer's eye, which is the proper position during use, the same is bent at 20. This will enable the user to get the apertured end of the tab behind his glasses if he uses such. In order to reduce to a minimum the amount of wear on the cord 17 when the same is being pulled out of and let into the case a roller 21 may be mounted in the opening of the casing as shown.

In use the instrument is opened up as shown in Figs. 1 and 2 and the cord 17 drawn out to full length, the tab 18 being placed close to the eye E (Fig. 1) so that the observer may look through the aperture 19 therein and through the slits 22 and 23 in the end portion of the cover 2. When these three openings and the observer's eye are in line with the object O (Fig. 1), the ob-

server then looks through prism 10 so he will see the object O through the scale S, etched in the face of the prism. This enables the user to read the distance directly and without resorting to the shifting of parts, which is a very great simplification over any prior device with which I am familiar. The enlargement 24 intermediate the ends of the slit 23 renders it much easier to get the two slits 22 and 23 in alignment with the object O. When the user has finished his observation, the spring or cord 17 is permitted to roll up on reel 15 and the end of the tab 18 is inserted in the cavity in end member 6, whereupon the shield 11 is turned on its pivot to enclose the tab within the casing 1. The cover 2 is then turned on its pivots 3 to close the two sides of the casing and the locking member 4 is moved into locking position to hold the parts closed.

It is of course understood that the specific description of structure set forth above may be departed from without departing from the spirit of my invention as set forth in this specification and the appended claims.

Having now described my invention, I claim:

1. In a distance finder, a base having a pair of vertically extending separated walls, a pair of vertically extending slits in said walls in position to determine a line of sight at substantially a right angle to the axis of the base, and means on said base at a distance from said slits and adapted to co-operate therewith in determining distances of objects.

2. In a distance finder, a base having a pair of vertically extending separated walls, a pair of vertically extending slits in said walls in position to determine a line of sight at substantially a right angle to the axis of the base, and means on said base at a distance from said slits and adapted to co-operate therewith in determining distances of objects, one of said slits having intermediate its ends an enlargement to assist in sighting.

3. In a distance finder, a base for supporting sighting means and a graduated prism,

a flexible member for positioning said base at a given distance from an eye of the observer, and a tab secured adjacent the end of the said member, said tab being bent intermediate its ends to facilitate inserting one end behind glasses worn by an observer.

4. In a distance finder to be used at a fixed distance from an observer's eye, a cord of predetermined length to position the instrument at the proper distance and a tab secured adjacent the end of the cord, said tab being bent intermediate its ends to facilitate inserting one end thereof back of the observer's glasses.

5. In a distance finder, a casing, a prism fixed therein, and a cover hinged thereto and adapted to fold over to cover the open faces of the casing, said cover having near its free end a pair of separated slots adapted to serve as sighting means.

6. A distance finder comprising a casing closed at its ends and sides and open at its edges, a prism secured therein between the open edges, and a box-like cover hinged adjacent one end and adapted to fold over to cover opposite exposed faces of the prism.

7. A distance finder comprising a casing closed at its ends and sides and open at its edges, a prism secured therein between the open edges, said casing having a cavity in one end between the exterior thereof and the adjacent end of the prism, a spring actuated reel carrying a cord to be wound thereon mounted in said cavity of said casing, and a cover hinged adjacent one end and adapted to fold over to cover the open edges.

8. A distance finder comprising a casing closed at its ends and sides and open at its edges, a prism secured therein between the open edges, a shield pivoted to the casing at one end of one of the open edges to close the same when not in use, a spring actuated reel carrying a cord to be wound thereon mounted in one end of said casing, and a cover hinged adjacent one end and adapted to fold over to cover the open edges.

In witness whereof, I hereunto subscribe my name to this specification.

JAMES MURRAY WASHBURN.
